RING-STYLE CAP OPENER OR SIMILAR ARTICLE

Haruo Matsumoto, 783-92 Shimabiraki Tonnouchi,
Amagasaki, Japan

Filed Mar. 9, 1972, Ser. No. 233,389

Term of patent 14 years

Int. Cl. D7—06

U.S. Cl. D8—40

FIG. 1

FIG. 3

FIG. 1 is a front elevational view of the ring-style cap opener showing my new design;

FIG. 2 is a top plan view thereof;

FIG. 3 is a bottom view thereof; and

FIG. 4 is a sectional view taken along the line 4—4 in FIG. 2.

I claim:

The ornamental design for a ring-style cap opener or similar article, substantially as shown and described.
